JACOB ROBERTS, OF CATASAUQUA, PENNSYLVANIA.

KILN, FURNACE, &c.

SPECIFICATION forming part of Letters Patent No. 723,310, dated March 24, 1903.

Application filed November 12, 1896. Serial No. 611,828. (No model.)

To all whom it may concern:

Be it known that I, JACOB ROBERTS, of Catasauqua, in the county of Lehigh and State of Pennsylvania, have invented a certain new 5 and useful Improvement in Kilns, Furnaces, &c., of which the following is a specification.

The present invention relates to improvements in kilns, furnaces, boilers, &c., and is especially designed for the purpose of causing 10 a more perfect combustion of the fuel used for the generation of heat. This object I effect by injecting a supply of oxygen upon the gases formed by the heating of the fuel, and this I preferably do by throwing a blast 15 of cold air upon the combustible gases generated from the fuel at a point beyond the generation of said gases.

It is well known to me that many devices have been employed for the purpose of throwing 20 into a furnace-space an additional supply of oxygen; but all these devices have proceeded on the theory that the best results may be obtained by passing hot air into the furnace-space, and for this purpose air has been 25 led through heating-pipes or through hollow grate-bars and discharged upon the heated fuel and gases at different points beyond the point of consumption of the fuel. I have discovered, however, that in these processes the 30 oxygen is partially consumed during its passage through the heating pipes without giving any beneficial results. In my apparatus, on the other hand, cold air carrying its full proportion of oxygen is injected on the heated 35 gases, which still hold unconsumed carbon, at a point beyond the generation of such gases, and this injection of cold air carrying oxygen upon the heated gases causes a combustion thereof.

40 In the drawings I have illustrated the application of my invention to a brick-kiln.

Referring to the drawings, Figure 1 is a vertical section of a brick-kiln along the line 1 1 of Fig. 2. Fig. 2 is a horizontal section along the broken line 2 2 of Fig. 1.

Referring to the drawings in detail, 1 represents the wall of a brick-kiln, and 2 2 represent fire-boxes for the same, which fire-boxes may be of any desired construction.

50 3 designates a pipe surrounding the kiln and provided with branch pipes 4, projecting downwardly, and also branch pipes 5, project-

ing upwardly from the pipe 3. Pipe 3 is in communication with a blower or fan and serves as a main feeder to branch pipes 4 and 5. The branch pipes 4 are each provided with a mouth 6, which may be trumpet-shaped or having one of its sides flaring, and which opens on the inside of the kiln at a point slightly above the fire-boxes. The pipes 4 also 55 lead down and supply air under pressure to a point below the grate-bars, as seen in Fig. 1. The pipes 5 extend to the top of the kiln and project their currents of air upon the top of the contents of the brick-kiln. The pipes 5 60 are also provided with mouths similar in form to the mouths on the pipes 4, and these mouths, as well as those of the pipes 4, which open upon the inside of the kiln, are inclined 65 in such a manner as to project their currents 70 of air spirally around the interior of the kiln. By this means a continuous current of air spirally winding around and around the interior of the kiln is caused, whereby the fullest effect of the combination of the oxygen with 75 the carbonaceous gases is produced.

In operating the device I first open the pipes 4, so that the current of air is applied to the fire-boxes at the bottom of the grate-bars and also at a point just above the fire-boxes on the interior until the contents of the kiln have become ignited to a considerable degree, whereupon as the gases now ascend, holding unconsumed carbon, I open the pipes 5, so as to inject an additional supply of oxygen 80 upon the gases at the upper part of the kiln.

What is claimed as new is—

1. A kiln having a series of air-conduits intermediate the top and bottom of the walls 90 thereof, a series of similar conduits opening above the charged furnace-space, inclined flaring mouths to said conduits, opening upon the furnace-space, said mouths being so inclined as to project the current of air issuing 95 therefrom in the same direction to produce a spiral motion of the air-currents inside the furnace substantially as specified.

2. A circular kiln having a series of fire-boxes arranged at regular intervals about the 100 exterior of the kiln and provided with flaring mouths opening into the furnace-space thereof, a series of air-conduits adapted to supply air under pressure and containing the normal

quantity of oxygen, below the grate-bars of the fire-boxes and a series of similar conduits opening into the furnace above the fire-boxes and intermediate the top and bottom walls thereof, and also provided with flaring mouths opening upon the furnace-space, said mouths being so inclined as to project the currents of air issuing therefrom in the same direction to produce a spiral motion of the currents inside the furnace.

3. The combination with a circular kiln, of a plurality of fire-boxes arranged exterior to and having flaring mouths opening into the furnace thereof, a series of air-conduits supplying air under pressure below the grate-bars of the fire-boxes, a series of similar conduits opening into the furnace above the fire-boxes and intermediate the top and bottom

walls of the furnaces, and another series of similar conduits opening into the kiln above the charging-space thereof, said conduits adapted to supply air containing the normal quantity of oxygen to the fire-boxes and to the kiln, and formed with inclined flaring mouths opening upon the furnace-space, said mouths being so inclined as to project currents of air issuing therefrom in the same direction to produce a spiral motion of the currents inside the furnaces.

In testimony whereof I have signed my name to this specification in the presence of two subscribing witnesses.

JACOB ROBERTS.
